UNITED STATES PATENT OFFICE.

PHILIP D'H. DRESSLER, OF ZANESVILLE, OHIO, ASSIGNOR TO AMERICAN DRESSLER
TUNNEL KILNS, INC., OF NEW YORK, N. Y., A CORPORATION OF NEW YORK.

COMBINED MUFLLE AND OPEN TUNNEL KILN.

1,360,626.

Specification of Letters Patent. Patented Nov. 30, 1920.

Application filed May 28, 1919, Serial No. 300,443. Renewed May 18, 1920. Serial No. 382,334.

To all whom it may concern:

Be it known that I, PHILIP D'H. DRESSLER, a subject of the King of Great Britain, and resident of Zanesville, in the county of Muskingum and State of Ohio, have invented 5 certain new and useful Improvements in Combined Muffle and Open Tunnel Kilns, of which the following is a specification.

My present invention relates to continuous 10 tunnel kilns and the general object of the invention is to effect an advantageous combination of constructive features and advantages of two distinct types of tunnel kilns; one of these two types of tunnel kilns being the 15 open fire type in which all or the major portion of the heating of the goods is accomplished by direct contact of the goods with hot gaseous products of combustion, while the other type is that type in which the heating 20 of the goods is accomplished mainly or wholly by convection currents of the kiln chamber atmosphere passing through or along the goods and about combustion chambers in which combustion occurs and from 25 which the products of combustion are withdrawn without passing into the kiln chamber proper and without coming into contact with the goods.

The various features of novelty which 30 characterize my invention are pointed out with particularity in the claims annexed to and forming a part of this specification. For a better understanding of the invention, however, and the advantages possessed by it reference should be had to the accompanying 35 drawings and descriptive matter in which I have illustrated a preferred embodiment of my invention.

Of the drawings:

40. Figure 1 is a somewhat diagrammatic plan of a kiln.

Fig. 2 is a plan of a portion of the apparatus shown in Fig. 1, taken on a larger scale than Fig. 1, and with parts broken away and 45 in section.

Fig. 3 is an elevation in section on the line 3—3 of Fig. 2.

Fig. 4 is an elevation on the section of the line 4—4 of Fig. 2, and

50. Fig. 5 is a view taken similarly to Fig. 1 illustrating a modification.

In the drawings, and referring first to Figs. 1-4, A represents the kiln proper and B, C and D represent successive sections of

the kiln chamber. The goods G to be treated 55 are mounted on cars F running on track rails E which extend through the three sections of the tunnel kiln chamber. The goods carrying cars F enter the kiln chamber through the outer end of the section B, which is preferably provided with double doors K and K¹ forming an air lock. The cars thus entering the kiln are moved slowly through the latter and issue at the outer end of the section D which may advantageously be provided with a door K_A. I have not disclosed any mechanism for moving the cars through the tunnel as the details of such mechanism form no part of my present invention, and mechanisms suitable for the purpose are well 60 known and in common use. It will be understood that the tunnel is normally filled with goods carrying cars K one being taken out of the kiln past the door K_A every time a car is inserted in the kiln past the doors K and 65 K¹. To prevent the circulation of hot gases along the track rails E and the wheels and other lower parts of the cars F, the well known expedient is employed of providing the cars with flanges F¹ at their sides dipping 70 into sand seals in stationary troughs F².

The intermediate kiln section C, is laterally enlarged and horizontally elongated combustion chambers H are located in the lateral enlargement of this kiln section at 85 the sides of the path-way for the goods G. At the ends of the combustion chambers adjacent the outlet door K_A fuel gas supply pipes I open into the combustion chambers. Air for the combustion of this gas is admitted to the kiln chamber at the outlet end of the chamber as by means of ports L formed in the door K_A. A draft is created tending to create a gaseous flow from the air inlet ports L at the opposite end of the 90 kiln chamber by suitable means, as for instance, the exhaust fan M shown as connected to the kiln chamber adjacent the door K¹ by the bifurcated pipe N. To force a large portion of the air thus drawn through 100 the kiln to pass into the combustion chambers H, and through the latter instead of through the clearance space between the goods G and the adjacent walls of the kiln chamber section C and combustion chambers 105 H, one or more baffles O are provided at the corresponding ends of the combustion chamber which fit closely about the goods on the

cars F. The kiln wall is also advantageously inclined as indicated at C¹, to facilitate the ready flow of air into the combustion chambers. At the opposite ends of the combustion chambers, the kiln wall is similarly inclined as indicated at C² to avoid eddies and friction impeding the flow out of the combustion chambers and, in practice, the kiln wall at C² should be lined with highly refractory material to avoid deterioration under the high temperatures of the gaseous products leaving the combustion chambers. The combustion chambers are so disposed with respect to the walls of the kiln chamber 15 as to permit the circulation of convection currents upward past the combustion chambers and downward through and along the goods. For this purpose the walls of the combustion chamber may advantageously be 20 formed as in the well known Dressler kiln, of sections of hollow tile. Passages H¹ in the tile sections unite to form paths of flow about the combustion chambers while at the same time the goods are shielded against 25 the direct radiation of heat from the inside walls of the passages H¹.

In operation, the fan M or other draft producing device causes a continuous gaseous flow from the air inlet ports L through the 30 section D of the kiln chamber to the adjacent ends of the combustion chambers H. The air thus brought to the combustion chambers enters the latter and unites in combustion therein with the fuel gas supplied 35 through the fuel gas inlets I. The combustion chamber H should be of such a length say 20 or 30 feet in ordinary practice that the fuel gas will be entirely burned in the combustion chambers and a large portion of 40 the heat of combustion will be withdrawn from the products of combustion and delivered to the goods through the medium of the convection currents flowing through the passages H¹ and through or along the goods. 45 The partially cooled products of combustion issuing from the exit ends of the combustion chambers pass into the adjacent end of the kiln chamber B and pass longitudinally of the latter to the outlet pipes N. 50 The products of combustion entering the kiln chamber section B are gradually cooled in their passage through the latter, imparting their heat to the goods G in this section of the kiln.

55 The construction shown in Figs. 1-4 is intended for use where the goods after passing through the high temperature zone of the kiln are cooled down to a substantial extent before being taken out of the kiln. 60 This is generally the case for instance where the kiln is used in firing pottery. In other cases however, as for example in the glass industry and in steel heating furnaces it is desirable to withdraw the goods from the 65 kilns while still at the maximum tempera-

ture attained in the kiln. For such cases the form of my invention illustrated in Fig. 5 is well adapted.

The kiln A A shown in Fig. 5 differs from that shown in Figs. 1-4 inclusive essentially 70 in that the cooling section D of the kiln shown in Figs. 1-4 is omitted. In Fig. 5 the goods outlet door ha is placed immediately adjacent the exit end of the high temperature section C of the kiln, and advantageously a second door ha forming an air lock is provided. The air, uniting in combustion with the gas supplied by the pipes I, is admitted to the combustion chambers through air inlets LA. This air may 80 be drawn directly from the atmosphere or may be preheated as conditions require or make desirable.

With each of the constructions described I obtain the following characteristic advantages of a kiln having combustion chambers of the Dressler type: namely, the indestructibility of the combustion chambers due to their thin wall construction and the abstraction of heat therefrom by convection currents; the good distribution of heat in the high temperature zone of the kiln resulting from the fact that the heat transfer from the combustion chambers is mainly by convection currents in the fluid medium 95 through which the goods are moved and not by radiation from hot walls or by direct contact with the burning products of combustion; and a sufficiently elongated high temperature zone to permit an adequate exposure of the goods to the highest kiln temperature with a reasonably rapid rate of travel of the goods carrying cars through the tunnel I also obtain the following advantages characteristic of open fire kilns; 100 namely, a shorter length of kiln than is required if substantially all of the heat imparted to the goods is transmitted by conduction through combustion chamber walls; and a cheapening of construction due both to 105 the shortening of the kiln as a whole, and also to the shortening of the combustion chambers relative to the length of the kiln.

Certain novel features characterizing the apparatus disclosed herein and also characterizing other forms of apparatus devised by me are claimed generically in my co-pending application, Serial No. 353976 filed January 26, 1920.

While in accordance with the provisions 120 of the statutes I have illustrated and described the best form of my invention now known to me it will be apparent to those skilled in the art that changes may be made in the form of the apparatus disclosed without departing from the spirit of my invention as set forth in the appended claims and that certain features of my invention may sometimes be used to advantage without a corresponding use of other features.

Having now described my invention, what I claim as new and desire to secure by Letters Patent, is:—

1. The combination in a tunnel kiln having an elongated kiln chamber comprising two sections placed end to end, of a combustion chamber separate from the kiln chamber, extending longitudinally of the kiln and located in one of said sections and open to the other section at the junction of the two sections, means for supplying air and fuel to the end of the combustion chamber remote from said other section and means for creating a draft through said other section tending to draw the products of combustion out of said combustion chamber and through said other section.
2. In a tunnel kiln, the combination with an elongated kiln chamber having an air inlet at one end and having a laterally enlarged portion intermediate of its ends, a combustion chamber separate from the kiln chamber, extending longitudinally of the kiln and located in said laterally enlarged portion of the kiln chamber and open to the latter at each end of said enlarged portion, means for supplying fuel to said combustion chamber and means for creating a draft through said kiln chamber from the end at which the air inlet is located toward the opposite end of the kiln chamber.
3. In a tunnel kiln, the combination with an elongated kiln chamber having an air inlet at one end and having a laterally enlarged portion intermediate of its ends, a

combustion chamber separate from the kiln chamber, extending longitudinally of the kiln and located in said laterally enlarged portion of the kiln chamber and open to the latter at each end of said enlarged portion, means for supplying fuel to said combustion chamber, means for creating a draft through said kiln chamber from the end at which the air inlet is located toward the opposite end of the kiln chamber, and a baffle across the kiln chamber adjacent the end of the combustion chamber toward said air inlet for directing the air from said inlet into said combustion chamber.

4. In a tunnel kiln, the combination with an elongated kiln chamber having an air inlet at one end and having a central laterally enlarged portion connected by tapering portions to end portions of the chamber, a combustion chamber separate from the kiln chamber, extending longitudinally of the kiln and located in said laterally enlarged portion of the kiln chamber, and open to the kiln chamber at each end of said enlarged portion, means for supplying fuel to said combustion chamber, and means for creating a draft through said kiln chamber from the end at which the air inlet is located toward the opposite end of the kiln chamber.

Signed at city of Zanesville, in the county of Muskingum and State of Ohio this 19th day of May, A. D. 1919.

PHILIP D'H. DRESSLER.

Witness:

C. T. MARSHALL.
